UNITED STATES PATENT OFFICE.

LAWRENCE M. PERSONS, OF CHICAGO, ILLINOIS, ASSIGNOR TO COOK ELECTRIC COMPANY, OF CHICAGO, ILLINOIS, A CORPORATION OF ILLINOIS.

FLOAT-OPERATED SNAP-OVER SWITCH.

Application filed May 31, 1924. Serial No. 717,135.

My invention relates to electric switches and more particularly to an improved float operated snap-over switch.

An object of my invention is to produce a float operated snap-over switch of exceeding simplicity which is certain and efficient in operation and devoid of delicate mechanism which is apt to require constant and frequent repair.

10 In carrying out my invention, I prefer to position the switch between the lower end of the float and a parallel support extending beneath the surface of the liquid, so that the switch in effect serves as an interconnection between these parts at this point. This arrangement permits a definite minimum movement of the float, such as is necessary to operate the switch.

15 A further object of my invention is to arrange a spring of the snap-over switch so that the upward movement of the float is resisted until the resultant upward pressure of the liquid (or buoyancy) overcomes the spring. As the switch elements are biased beyond dead center, the float assumes a definite and positive movement upward, which is sufficient to move the contact member with a snap action to off-position. The spring also resists the downward movement of the float as the level lowers, until the resultant upward pressure of the liquid is again overcome but by the weight of the float in this instance. In a similar manner the contact member will move to on-position and the circuit quickly closed 30 to effect pumping of the liquid into the receptacle.

35 I wish to point out the compact arrangement of the parts, their simplicity and the resulting economy, both in space and material. The receiving receptacle may be made smaller without lessening its capacity due to the decreased space occupied by the device.

40 In order to apprise those skilled in the art how to construct and practice my invention, I shall now describe an embodiment thereof in connection with the accompanying drawings.

In the drawings—

45 Figure 1 is a side elevational view of a float operated electric switch disposed within a fluid container;

50 Fig. 2 is a perspective view of a support

adapted to extend beneath the surface of the liquid for carrying the float and switch;

Fig. 3 is a top plan view of a float mechanism;

Fig. 4 is a bottom plan view of the same illustrating the snap-over switch;

Fig. 5 is a detail sectional view taken on line 5—5 of Fig. 4;

Fig. 6 is a detail sectional view of the contact carried by the float support; and,

Fig. 7 is a sectional detail view of an insulated mounting of a float mechanism taken on line 7—7 of Fig. 1.

The float mechanism embodying my invention and associative with the snap-over switch, disclosed herein, comprises a support 2, the lower end of which extends beneath the surface of the liquid so that it will remain submerged. A float 3 is adapted to be connected at its upper and lower ends to support 2. Support 2 preferably comprises a U-shaped member having its sides cut away to form openings 4. In the openings 4, the float 3 is adapted to move, which movement is restricted by lateral extensions 5. Flanges 6 extend transversely from the sides of support 2 and are apertured at 7 to receive bolts 8. As illustrated in Fig. 1, the bolts 8 are adapted to project downwardly from a wall 9, which in this instance serves as a mounting for the float mechanism.

In the device disclosed, frame 2 may constitute one side of the circuit. The bolt 8 is, therefore, insulated from the support 2 by the provision of an insulated collar 10 seating in the apertures 7, and by a pair of insulation washers 11 separating the support 2 from the wall 9 and the nut 12 at the end of bolt 8.

Support 2 is preferably of a metal stamping so that it will be light and inexpensive to manufacture. To permit an efficient circulation of fluid about support 2 so that any variation in the liquid level will immediately effect the float 3, the back wall 13 of support 2 is apertured at 14. This also tends to increase the lightness of the float mechanism.

Float 3 is of standard construction, but is of definite size and proportions. At the top and bottom of float 3, U-shaped brackets are attached so as to provide projecting apertured ears 15. The upper extensions 5 of support 2

are apertured at 16', which, together with the apertured ears 15, receive an interconnecting yoke member 16. As will be noted in Fig. 3, yoke member 16 is provided with the legs 17, the outer ends of which engage in the apertures 16'. The yoke member 16 is also provided with the lateral ears 18, which are adapted for reception in the apertured ears 15.

10 At the lower end, a snap-over switch 25 is disposed between the support 2 and the float 3. The switch elements comprise a pair of yoke members 26 and 27, pivoted at adjacent points in the lower lateral extensions 5. Yoke member 26 serves as the contact member of the switch, but yoke member 27 comprises the interconnecting means between support 2 and the lower end of float 3. As will be noted in Fig. 4, a coil spring 28 spans the yoke members 26 and 27, the ends of which spring engage in notches 29 for retaining this spring centrally between the yoke members 26 and 27. The spring 28 tends to draw together the opposite ends of the yoke members when 25 they are biased in either direction from their dead center relation. When biased in an upward direction, the spring 28 acts to draw the contact 26 upwardly against a stop 30, as illustrated in Fig. 5. Stop 30 in the present 30 case comprises the portion of the lower edge of the back 13 turned inwardly a distance sufficient to intercept the contact 2 before reaching the limits of its upward movement.

When the yoke members 26 and 27 are 35 biased in a downward direction from their dead center relation, the contact yoke member 26 engages a terminal 31 to which the lead-wire 32 is connected, this being clearly shown in Fig. 2. I have illustrated in detail in 40 Fig. 6, however, a sectional view of terminal 31. A bolt 33 passes through an insulated aperture 34 in the back wall 13 of support 2, while fiber washers 35 serve to space the lead-wire 33 and a terminal lug 36 away from this 45 wall 13.

Lug 36 is also positioned to intercept contact member 26 before reaching its lower limit of movement.

It will be noted that by disposing the snap-over switch between the submerged lower end of support 2 and the lower end of float 3, the switch will always remain submerged. The particular arrangement of the parts 26 and 27 and the spring 28 prevents float 3 from 50 assuming a gradual movement with the rise and fall of the liquid level in the receptacle. However, the float is under control of the liquid level. With the float in its lower position, as illustrated in Fig. 1, the contact 55 member 26 is in engagement with the terminal lug 36 to close the circuit. The pump for pumping the liquid into the receptacle then operates until a predetermined level, say line A-B indicated in Fig. 1, is reached. This 60 level is such that the resultant upward pres-

sure of the liquid against the submerged portion of float 3 is sufficient to overcome spring 28 tending to draw together in a downward direction the opposite ends of the yoke members 26 and 27. This resultant fluid pressure 70 raises yoke member 27 beyond the dead center relation, and in so doing overcomes the resistance of the spring. When moving beyond this dead center relation, the spring rapidly draws contact member 26 out of engagement 75 with the terminal lug 36. Thus the contact is quickly broken. It will be noted that the spring will accelerate the movement of float 3 when moving beyond dead center.

The same action takes place in the downward travel of the float. When the resultant upward pressure of the fluid is no longer sufficient to sustain the weight of float 3, say the level indicated at C-D in Fig. 1, the float will drop by gravity, bringing the yoke 85 member 27 beyond its dead center relation with the contact member 26. Thus, the spring will bring the contact member into snap engagement with the terminal lug 36 to close the circuit. One side of the circuit 90 denoted by the lead-wire 38 is grounded to the frame at 39.

From the foregoing description it will be apparent that I have provided an improved float operated switch which is associable with 95 a float mechanism having a float provided with a definite minimum movement to operate the switch. If desired, my device may be employed in receptacles of any size. It will be noted that the support 2 is in parallel 100 relation with the float 3 and that the float 3 moves substantially in a perpendicular plane. Lateral extensions 5 serve as stops to limit the movement of float 3 as soon as contact member 26 is thrown past dead center relation in either direction. This restricts the 105 float to a minimum movement which requires less space for its operation.

Without further elaboration, the foregoing will so fully explain the gist of my invention, 110 that others may, by applying current knowledge, readily adapt the same for use under varying conditions of service, without eliminating certain features which may properly be said to constitute the essential items of 115 novelty involved, which items are intended to be defined and secured to me by the following claims.

I claim:

1. A float operated submerged snap switch 120 for use within tanks containing combustible liquid or the like comprising a support extending beneath the surface of the liquid, a pair of oppositely extending yoke members pivotally mounted on said support, spring 125 means tending to draw together the opposite ends of said yokes when said yokes are biased in either direction from a dead center relation, a contact upon said support submerged in the liquid and in the path of one of said 130

yokes, and a float for tilting the other of said yokes for effecting a quick make and break of the circuit at said contact.

2. A float operated snap-over switch for 5 use in a liquid container comprising a support provided with side openings in which a float is adapted to move and to have limited perpendicular movement, a connection at each end of the float for loosely securing the 10 same to the support, and contact members one of which is interconnected to one of said connections so as to effect movement of the contact member upon movement of the float.

3. A float operated snap-over switch for 15 use in a liquid container comprising a support and a float connected thereto at each end, contact members one of which is pivoted to said support at its lower end, and means for operating said pivoted contact member through 20 the lower float connection upon movement of the float.

4. A float operated snap-over switch having circuit making and breaking elements for use in a liquid container comprising a support 25 provided with spaced lateral extensions arranged in pairs at the upper and the lower ends, a float movable between the upper pair and the lower pair, a yoke member bridged across said upper pair and pivotally connecting 30 the float to the support, a second yoke member bridged across the lower pair and pivotally connecting the float to the lower end of the support, and a third yoke member constituting one of the circuit making and 35 breaking elements of the switch interconnected with said second yoke member for operation upon movement of the float.

5. A float mechanism, embodying an electric switch adapted to be operated thereby, 40 and capable of detachment from its mounting as an assembled unit comprising a float, a frame member arranged to limit the movement of the float between the ends of the

frame member, and loose pivotal connections between said ends of the frame member and 45 the ends of the float.

6. A float mechanism for operating an electric switch adapted to be detachable as a unit from its mounting comprising a frame member provided with a side opening in which 50 the float is adapted to move, and an electric switch serving as the interconnecting means between one end of the frame member and the float.

7. In combination, a float, a parallel support 55 extending beneath the surface of the liquid, and a snap-over switch arranged between said float and said support at the lower end for operation upon movement of the float.

8. In combination, a float, a parallel support 60 extending beneath the surface of the liquid and connected to said float at each end, and a snap-over switch arranged at the lower end of said float for operation upon movement of the float.

9. In combination, a float, a parallel support 65 extending beneath the surface of the liquid, means for connecting the ends of the float with said support, and lateral projections on the ends of said support for serving 70 as stops to restrict the movement of said float.

10. A float controlled switch comprising a support, a pair of oppositely arranged members connecting one end of the float to said support, said support providing pivotal 75 mountings for said members at their adjacent ends whereby the other ends are movable, one to contact with a terminal of the circuit and the other pivotally to connect to the float, and an over-center spring for initiating and 80 thereafter accelerating the opening and closing movements of said terminal contacting member imparted thereto by said float.

In witness whereof, I have hereunto subscribed my name.

LAWRENCE M. PERSONS.
